ATTORNEY

UNITED STATES PATENT OFFICE.

STEVE MEDVETZ, OF HOMER CITY, PENNSYLVANIA.

DESIGN FOR A CHRISTMAS-TREE ORNAMENT.

56,372.

Specification for Design.

Patented Oct. 5, 1920.

Application filed March 19, 1920. Serial No. 367,210. Term of patent 7 years.

To all whom it may concern:

Be it known that I, STEVE MEDVETZ, a citizen of the Republic of Czechoslovakia, residing at Homer City, in the county of Indiana and State of Pennsylvania, have invented a new, original, and ornamental Design for a Christmas-Tree Ornament, of which the following is a specification, reference being had to the accompanying drawings, forming a part thereof.

The figure is a perspective view of a Christmas tree ornament, showing my new design.

I claim:

The ornamental design for a Christmas tree ornament as shown.

STEVE MEDVETZ.
